DOOR LIFT MECHANISM

Frank Ditchfield, Cleveland, Ohio, assignor to
The Youngstown Steel Door Company, Cleve-
land, Ohio, a corporation of Ohio

Application May 6, 1943, Serial No. 485,825

7 Claims. (Cl. 16—99)

This invention relates to door lift mechanisms and is directed primarily to lift mechanisms which are applied to the structure on which the door is mounted rather than upon the door.

It is an object of this invention to provide lift mechanisms of the character indicated which shall be sturdy, easy to operate, eliminate castings, and involve a reduction in cost over lift mechanisms now in use.

A further object is to provide lift mechanisms of the character indicated which shall embody continuous door tracks associated with the mechanisms in protective relationship.

A further object is to provide lift mechanisms of the character indicated which shall embody continuous door tracks and attaching brackets capable of assembly into a unit for application to the desired structure.

Other objects of the invention will become clear as the description thereof proceeds.

In the drawings forming part of this specification:

Fig. 1 is a fragmentary elevation with parts broken away of a railway house car showing a door lift mechanism embodying the invention applied thereto, the door being shown in lowered position.

Fig. 2 is a vertical section taken on line 2—2 of Fig. 1.

Fig. 3 is a horizontal section taken on line 3—3 of Fig. 2.

Fig. 4 is a vertical section taken on line 4—4 of Fig. 2.

Fig. 5 is a view similar to Fig. 4 showing the door in elevated position.

Fig. 6 is a vertical section taken on line 6—6 of Fig. 1.

Fig. 7 is an elevation of the inner bracket member.

Fig. 8 is an elevation of the outer bracket member.

The lift mechanism embodying the instant invention is shown applied to a railway house car 10 illustrated fragmentarily in the drawings. As illustrated the car embodies metallic sheathing 11 secured along its lower margin as by means of rivets 12 to the upstanding flange 13 of an angle side sill 14. The side sill embodies also an inwardly extending horizontal flange 15 upon which the floor 16 of the car is adapted to be supported. This side sill 14 is reinforced through the customary door opening and for a portion beyond the rear of the door opening by means of a side sill reinforcement 17 illustrated

in Fig. 2 of the drawings as a bulb angle, the horizontal flange 18 of which is secured to the horizontal flange 15 of the side sill in any desired manner. The vertical flange 19 of the bulb angle extends downwardly and provides a base for the attachment of the lift mechanism of the instant invention.

This lift mechanism embodies a plurality of longitudinally and uniform spaced brackets 10 which are preferably identical in construction. Each of these brackets 20 comprises an inner member 21 formed preferably of sheet metal so as to include a web 22, side walls 23 and 24 and oppositely extending attaching flanges 25 and

26. As more clearly illustrated in Figs. 5 and 7, the web 22 of the inner bracket member 21 extends above the side walls and attaching flanges. The bracket 20 comprises also an outer bracket member 27 formed preferably of sheet metal so

20 as to include a web 28, side walls 29 and 30, and oppositely extending attaching flanges 31 and 32. As more clearly shown in Fig. 3 of the drawings, the inner and outer bracket members 21 and 27 are associated in overlapping relationship with

25 the respective attaching flanges overlapping and being secured to the vertical flange 19 of the side sill reinforcing member 17 as by means of rivets 33 and 34. The webs 22 and 28 of the bracket members are spaced laterally from each other. The side wall 30 of the bracket member

30 is notched, as indicated at 35 in Figs. 4 and 5 of the drawings, for a purpose which will hereinafter appear. As more clearly shown in Fig. 2 of the drawings, the web 28 and the side walls

35 29 and 30 extending from the web 28 to the web 22 of the bracket member 21 lie below the upper end of the attaching flanges 25 and 26. The side walls 29 and 30 then extend upwardly as indicated at 35 to the upper end of the attaching flanges 25 and 26 so that the attaching flanges 31 and 32 of the outer bracket 27 are of the same height as the attaching flanges 25 and 26 of the inner bracket member 21.

An angle member 36 is secured to the web 22 45 of the inner bracket member 21 as by means of rivets 37 which extend through the web 22 and the vertical leg 38 of the angle member. The other leg 39 of the angle member extends outwardly and, as more clearly shown in Figs. 4 and 5 of the drawings, is formed to provide horizontal portions 40 and 41 connected by means of an inclined portion 42.

A similar angle member 43 is secured to the inner face of the web 28 of the outer bracket member 27. The securing is preferably ef-

fected by means of rivets 44 passing through the web 28 and the vertical leg 45 of the angle member. The other leg 46 of the angle member extends inwardly in opposed relationship to the leg 39 of the angle member 36 and is similarly formed so as to embody substantially horizontal portions 47 and 48 connected by an inclined portion 49. It will be observed, particularly from Fig. 2 of the drawings, that the legs 39 and 46 of the angle members 36 and 43 are spaced from each other.

A roller 50 is disposed between the pair of angle members carried by each bracket. Each roller 50 preferably carries a roller bearing (not shown) through which a pin 51 extends. Discs 52 and 53 are mounted on the pin 51 on either side of the roller 50 so that the ends of the pin project beyond the discs. The discs 52 and 53 are seated upon the legs 39 and 46 of the angle members 36 and 43.

The ends of each pin 51 are supported in a yoke member 54. As more clearly shown in Fig. 3 of the drawings, the yoke member 54 embodies a pair of substantially channel-shaped members 55 and 56 between which the roller and associated discs are received. The members 55 and 56 comprise also flanges 57 and 58 and flanges 59 and 60. The flanges 57 and 59 are opposed and spaced apart so as to receive between them and be secured to the flattened end 61 of a connecting pipe member 62. Similarly, the flanges 58 and 60 are opposed and spaced apart so as to receive between them and be attached to the flattened end 63 of a connecting pipe 64. In this manner the rollers 50 are connected together for simultaneous operation.

In the illustrated preferred embodiment of the invention the brackets 20 support a continuous track 65. As illustrated the track 65 is channel-shaped in section and embodies a web 66 and downwardly extending side walls 67 and 68. The side wall 67 is secured to the web 28 of the outer bracket member 27 by means of a plate member 69 and the side wall 68 is secured directly to the web 22 of the inner bracket member 21, as more clearly shown in Fig. 2 of the drawings.

The web 66 of the track 65 is so disposed that when the rollers are in the position shown in Figs. 1 and 4 of the drawings, it will lie above the rollers. Where the rollers occur the web 66 is cut away, as indicated at 70, so that the rollers may be projected above the web for a purpose which will hereinafter appear. It is to be understood that while a continuous track is preferred, the instant invention is not limited thereto. Separate track sections attached to the brackets may be utilized or, if desired, the track or track sections may be dispensed with entirely and the brackets used directly as door supporting means.

The track 65 is adapted to frictionally support a sliding door 71 in any position of the door. The door illustrated is of well known construction and need not here be described in detail except to point out that an angle member 72 is secured to the lower portion of the door between the panel 73 and the backing plate 74. The horizontal leg 75 of the angle member 72 is adapted to engage the web 66 of the track when the door is being frictionally supported thereby. Also secured to the bottom of the door are a plurality of spaced retaining brackets, one of which is shown at 76. These retaining brackets are substantially Z-shaped in section and embody a web 77 adapted to engage the web 66 of the track and a depending flange 78 adapted to lie between the side wall 68

of the track and the side sill reinforcement 17 in order to prevent accidental disengagement of the door from the track.

In addition to the brackets hereinabove described the lift mechanism embodies a track supporting bracket 79 which serves to support the forward edge of the track. The bracket 79 embodies a pair of substantially Z-shaped members 80 and 81 having depending overlapping flanges 82 and 83 which are secured as by means of rivets 84 to the vertical leg 19 of the side sill reinforcing member. The upstanding flanges 85 and 86 of the Z-shaped members 80 and 81 are secured directly to the side walls 67 and 68 of the track 65 and are spaced apart so as to receive an operating member 87.

The operating member 87 is preferably a length of pipe one end of which is flattened, as indicated at 88, and pivotally secured between the flanges 57 and 59 of the adjacent yoke member 54, as indicated at 89. The other end of the operating member 87 is also flattened and pivotally secured to an operating lever 90 the lower end of which is pivotally mounted upon a member 91 fastened to the side sill reinforcement as more clearly shown in Fig. 1 of the drawings. In order to obtain pivotal securing of the operating member 87 to the lever a flange 92 of the well known front door stop 93 is coped, as indicated at 94.

As illustrated in Fig. 1 of the drawings, five roller brackets are ample for the support of the door. As indicated above, these brackets are uniformly spaced and are so arranged that the door when elevated will at all times be supported upon three rollers.

In order to move the door along the track it is first elevated above the track by means of the hereinabove described lift mechanism so that it will then be supported upon the rollers rather than upon the track. In order to elevate the door for movement upon the rollers the lever 90 is swung in a counter-clockwise direction as viewed in Fig. 1 of the drawings. Movement toward the left is thereby imparted to the operating member 87 and through it to all of the rollers and roller discs. In this movement the discs move up the inclined portions of the angle members 36 and 43 until they are supported upon the upper horizontal portions 40 and 47. In this movement of the discs the rollers 50 are projected upwardly through the openings 70 in the web 66 of the track so as to engage the horizontal flange 75 of the door angle member 72 and elevate the door 55 above the track. When so elevated the door may then be moved upon the rollers to any desired position. When it is desired to lower the door into frictional engagement with the track the operating lever is swung in clockwise direction as viewed in Fig. 1, whereupon the discs will move down the inclined portions of the angle member 36 and 43 so as to retract the rollers below the track 65. If desired, means may be provided to fasten the lever 90 in position when the door is elevated.

It is to be observed from the foregoing description that the track, supporting brackets and the lift mechanism may be assembled as a unit and then fastened to the side sill reinforcement. When the unit is secured to the side sill reinforcement the track lies in protective relationship to the rollers, discs and connecting members.

The notch 35, referred to hereinabove, is formed in the side wall 30 of the outer bracket member 75 so that the rollers 50 may assume their lower-

most position, as more clearly shown in Fig. 4 of the drawings.

Numerous changes and modifications in the details of the invention will be clear to those skilled in the art. It is intended, therefore, that all such modifications and changes be comprehended within this invention which is to be limited only by the scope of the claims appended hereto.

I claim:

1. Door lift mechanism of the character described comprising a plurality of longitudinally spaced brackets, laterally spaced walls on each bracket, a member secured to each wall, each member having a flange, a portion of said flange being inclined longitudinally, a roller disposed between said members, a pin extending through each roller, discs rotatably mounted on said pin on either side of each roller, said discs being seated upon said flanges, means disposed between said bracket walls connecting said pins, a track having a web and downwardly directed flanges secured to said brackets on opposite sides of said rollers, and a lever secured to said pin-connecting means, the web of said track having spaced openings to permit projection of said rollers above said web.

2. Door lift mechanism of the character described comprising a plurality of longitudinally spaced brackets, laterally spaced walls on each bracket, a member secured to each wall, each member having a flange, a portion of said flange being inclined longitudinally, rollers disposed between said members, means carried by said rollers, discs rotatably mounted on said means on either side of said rollers, said discs being seated upon said flanges, means disposed between said bracket walls connecting said roller means, a track having a web and downwardly directed flanges secured to said brackets on opposite sides of said rollers, and a lever secured to said connecting means, the web of said track having spaced openings to permit projection of said rollers above said web.

3. Door lift mechanism of the character described comprising a plurality of longitudinally spaced brackets, laterally spaced walls on each bracket, a member secured to each wall, each member having a flange, a portion of said flange being inclined longitudinally, rollers disposed between said members, means carried by said rollers, discs rotatably mounted on said means on either side of said rollers, said discs being seated upon said flanges, means disposed between said bracket walls connecting said roller means, a member secured to each bracket and having a

web and downwardly directed flanges disposed on opposite sides of a roller, and a lever secured to said connecting means, said web having an opening therein to permit projection of said rollers above said web.

4. Door lift mechanism of the character described comprising a plurality of longitudinally spaced brackets, means carried by said brackets, said means having longitudinally inclined portions, rollers, means carried by said rollers, discs rotatably mounted on said roller means, said discs being seated on said bracket means and movable along said inclined portions, said rollers being spaced from said bracket means, means connecting said roller means, and a lever secured to said connecting means.

5. Door lift mechanism of the character described comprising a plurality of longitudinally spaced brackets, laterally spaced members carried by each bracket, said members having longitudinally inclined portions, rollers disposed between said members, means carried by each roller, discs rotatably mounted on said means on either side of each roller, said discs being seated on said members and movable along said inclined portions, means connecting said roller means, and a lever secured to said connecting means.

6. In a railway house car having a door, a track carried by said car adapted to frictionally support said door, a plurality of pairs of laterally spaced members carried by said car, said members having longitudinally inclined portions, a roller disposed between each pair of members, means carried by each roller, discs rotatably mounted on said means on either side of each roller, said discs being seated on said members and movable along said inclined portions, said discs and rollers lying at the lower end of said inclined portions when said door is frictionally supported on said track, and means for moving said discs up said inclined portions, said rollers being projected above said track to elevate said door during said movement of said discs.

7. Door lift mechanism comprising supporting means, said means having a longitudinally inclined portion, a roller, means on said roller, means rotatably mounted on said roller means, said last mentioned means being seated upon said supporting means and movable along said inclined portion, said last mentioned means supporting said roller relative to said supporting means, and means for moving said last mentioned means along said inclined portion.

FRANK DITCHFIELD.
